UNITED STATES PATENT OFFICE.

PETER A. PETERSEN, OF WHITING, INDIANA, ASSIGNOR TO STANDARD OIL COMPANY,
OF WHITING, INDIANA, A CORPORATION OF INDIANA.

CANDLE-SUPPORTING CUP FOR CANDLE BASES.

Application filed July 7, 1922. Serial No. 573,803.

To all whom it may concern:

Be it known that I, PETER A. PETERSEN, a citizen of the United States, residing at Whiting, in the county of Lake and State of Indiana, have invented a new and useful Improvement in Candle-Supporting Cups for Candle Bases, of which the following is a specification.

The present invention relates to candle supporting cups for candle bases and will be fully understood from the following description thereof, illustrated by the accompanying drawings, in which:

Figure 1 is a vertical sectional view through a base of conventional form in which is mounted a candle cup in accordance with the present invention, the cup being likewise shown in section;

Fig. 2 is a side elevation of the cup; and
Fig. 3 is a plan view of the cup.

Referring more particularly to the drawings, in Figure 1 the numeral 5 indicates a candle base of any suitable material, for example, of a heat-softening plastic material such as wax, as described in the prior application of Craswell, Serial No. 537,929, filed February 20, 1922.

The candle base 5 is provided with a cylindrical opening 6 at the top, this opening serving as a seat and receptacle for the candle cup. In the form illustrated, the candle base 5 is likewise provided with a bore 7 extending downwardly from the cylindrical opening 6, the bore 7 being of smaller diameter than the opening 6.

The candle cup which seats in the opening 6 has a cylindrical body portion 8, at the upper edge of which is formed a flange 9. The cup is closed at the bottom, as indicated at 10. The dimensions of the cup are such that it seats in the opening 6 in the candle base with the flange 9 extending over and lying on the top of the latter. The sides of the cup are formed with inward projections, preferably in the form of indentations 11 and which may suitably be arranged in oblique rows, as shown more particularly in Fig. 2. On the base 10 of the cup is formed

a downwardly projecting member 12, which is illustrated as conical in form, and which projects into the bore 7.

The base diameter of candles of the same indicated commercial size may vary quite widely, particularly in larger candles, with the result that many candles will be held only loosely by a standard size candle cup, with a consequent danger of overturning, dripping and of fire. The inwardly projecting indentations 11 formed in the cup of the present invention permit candles to be held tightly, even though materially smaller than the diameter of the cup. Furthermore, the indentations provide means for locking the candle in the cup, as by forcing the candle downwardly into the cup and giving it a slight twist when it has seated, grooves of the bayonet type, as indicated at 13, are formed in the base of the candle itself and materially aid in holding the candle firmly in position.

The downward projection 12 from the bottom of the cup extending into the bore 7 in the candle base 5 holds the candle cup in its proper upright position even though, as occurs in many instances, one side of the opening 6 into which the candle cup is fitted may be deformed to a greater or less extent, for example, in the case of a base made of heat fusible material, by the heat of a low burning candle.

I claim:

The combination with a candle base having an opening at its top and a bore of smaller diameter extending downwardly therefrom, of a candle cup having a cylindrical body portion seating in the correspondingly shaped opening in the base and having a downwardly projecting member extending from its base and seating in the correspondingly shaped bore in the candle base, the cylindrical body portion of said candle cup being provided with a series of obliquely alined inwardly projecting indentations adapted to take into the candle and to assist in holding the same in place.

PETER A. PETERSEN.
